UNITED STATES PATENT OFFICE.

L. STANLEY BAIER, OF PORTLAND, OREGON.

SAFETY HEAD-GEAR.

1,391,753.

Specification of Letters Patent. Patented Sept. 27, 1921.

Application filed March 29, 1921. Serial No. 456,544.

To all whom it may concern:

Be it known that I, L. STANLEY BAIER, a citizen of the United States, residing at Portland, in the county of Multnomah and 5 State of Oregon, have invented a new and useful Safety Head-Gear, of which the following is a specification.

My invention relates to improvements in safety head gears in which a crown of 10 spring steel wire is provided with an aluminum vizor and an air cushion in the sweat band.

The objects of my invention are to produce a head gear which—

15 In external appearance is indistinguishable from an ordinary cap;

Can be very cheaply manufactured;

Is comfortable to wear;

Affords good ventilation; and

20 Protects the heads of ball players against injuries from base balls, as also the heads of workmen where danger from falling bolts, nuts, rivets, stones, and such like objects prevails.

25 I attain these objects with the mechanism illustrated in the accompanying drawing in which—

Figure I is a plan view of the entire head gear without the cloth covering.

30 Fig. II is a side elevation of Fig. I.

Fig. III is a section through Fig. I along the line A—A with the cloth covering in place.

Similar numerals refer to similar parts 35 throughout the several views.

The crown of my head gear comprises a plurality of meridional pieces of spring steel wire 1 attached to a polar ring 2 and also to an equatorial ring 3. Two or more latitudinal rings 4 of spring steel wire are thereupon distributed over the resultant semi-spherical shell. The crossing points of the meridional and latitudinal wires are spotwelded to form a rigid connection in regards to each other, 45 yet elastic when considering the shell as a whole. To the inner circumference of the equatorial ring is riveted, soldered or otherwise attached in any desired manner an aluminum band 5. Affixed to the latter in 50 any suitable manner is a leather sweat band 6; and held in the fold of the leather sweat band is a rubber cushion 7, oblong in cross section, and filled permanently with compressed air. A vizor 8, of conventional

shape and outlines is fitted to the rim at the 55 outside of the head gear and spotwelded where convenience permits.

The entire head gear may thereupon be covered with fabric 9 of any desired color or material. The place where the fabric is 60 sewed to the sweat band is indicated by a numeral 10, in Fig. III.

This device furnishes a very light head gear which possesses sufficient elasticity to repel small objects, and to regain its shape 65 after a slight distortion.

Having thus described my invention it will be seen that my objects have been accomplished, and, though I have shown the preferred form of construction I reserve to 70 myself the right to make minor changes, provided I do not violate the spirit and principle of my invention. Especially do I wish to emphasize that the meridional strands, instead of terminating at the polar 75 ring, may cross the pole from one side to the other in a semi-circle without being considered a transgression of the scope of this invention.

I claim.

1. In a safety head gear, the combination of a crown comprising a plurality of meridional strands and latitudinal rings both of spring steel wire, spotwelded at the crossing points, a metal vizor spotwelded to the 85 rim of the crown, and an air cushion at the rim within the crown.

2. In a safety head gear, the combination of a semi-spherical crown comprising meridional and equatorial spring steel wires spotwelded at their intersection, an aluminum vizor spotwelded to the rim outside of the crown, an aluminum band spotwelded to the rim within the crown, a leather sweat band attached to the aluminum band, and a rubber air cushion supported within the leather sweat band.

3. In a safety head gear, the combination of a crown formed of intersecting spring steel wires an aluminum vizor rigidly attached to the rim of the crown on the outside thereof, a rubber air tube attached to the rim within the crown, and textile fabric covering the crown and the vizor.

Signed by me at Portland, Oregon, this 105 22nd day of March, 1921.

L. STANLEY BAIER.
